UNITED STATES PATENT OFFICE

HERMANN FELGER, OF NUREMBERG, GERMANY

PROPELLED PENCIL

Application filed March 14, 1929, Serial No. 347,095, and in Germany March 21, 1928.

This invention relates to a propelling pencil with a lead holder made of four-cornered flat iron twisted in part to form a screw, the forward feed of which is effected by turning 5 a head which receives the four-cornered part of the piece of flat iron so that it cannot turn but can slide therein, the twisted part of the flat iron being guided by a nut fixed in the middle of the pencil. The propelling pencil 10 according to the present invention differs from the known propelling pencils of this kind in this, that the lead holder which is twisted to form a screw is guided in two slotted caps, one of which acts as a nut and is 15 fixed in the middle of the pencil, while the other is fixed in the head piece which is capable of rotating but not of sliding longitudinally. This arrangement of the propelling pencil constitutes a considerable improvement and makes it far simpler and 20 cheaper than those of a known kind. The entire mechanism of the propelling pencil consists only of the helically twisted flat iron strip and two slotted caps, which latter may 25 be made in a very simple manner by pressing or stamping and can be readily inserted in the casing of the propelling pencil.

In the accompanying drawings a constructional example of the invention is shown, 30 Fig. 1 showing the propelling pencil in axial section and Fig. 2 a portion of the twisted part of the bar with the slotted guide in perspective.

The propelling pencil contains as usual, 35 preferably enclosed in a celluloid or the like envelope 1, a casing 2, which tapers at the forward end and is provided at this tapered end 3 with a rifled opening for the lead 4. The lead 4 is carried by a short tube 5 which 40 is fixed to a flat bar 6. The flat bar 6 is twisted over about half its length to form a helix and the helical part 6a extends through a slot corresponding to the cross-section of the bar in the end of a cap 7 which is fixed inside the 45 casing 2. The untwisted rear end of the flat bar 6 slides in a slot, also corresponding to the cross-section of the bar, in the end of a second cap 8 which is connected to the rear end of the casing 2, so as not to slide therein, but to be capable of rotating therein, and

extends as to about half its length out of the casing. Over this cap 8 a hollow knob 9 is pushed, which is enclosed, similarly to the casing 2, with an envelope 10 of celluloid or the like and the outer wall of which is flush 55 with the outer wall of the casing 2.

On the knob 9 being turned, the cap 8 which is fixed to it is also carried round by this rotary motion, which is thus imparted to the flat bar 6. At the same time the bar 6 60 will turn with its helically twisted part 6a in the slot of the fixed cap 7 and will thereby be displaced longitudinally. The tube 5 together with the lead 4 will thus be pushed forward or backward according to the direction of rotation of the knob 9.

The backward motion of the lead 4 is limited by the distance between the rear end of the flat bar 6 and the inner surface of the 70 end wall of the knob 9. The backward motion of the flat bar 6 can only continue until its rear end strikes against this end wall of the knob 9. The distance to which the flat bar 6 and with it the lead 4 can slide with 75 respect to the casing 2 is adjusted when making the propelling pencil, by the distance to which the cap 8 and the knob 9 are pushed one over the other.

Through the lead carrier being made in the form of a bar with a twisted part and 80 through the employment of a fixed and a rotatable slotted guide for the said bar, the interior arrangement of the propelling pencil is greatly simplified, cheapened and improved as compared with the known pencils 85 of this kind. The twisted part may of course have any pitch, according to the desired rate of forward feed of the lead. All suitable materials may be used as the constructional material for the separate parts of the propelling pencil.

What I claim is:

A propelling pencil comprising the combination with a casing having an opening for the lead in one end thereof and a lead holder in said casing including a flat bar twisted to 90 form a screw, of guiding means for said lead holder comprising a cap fixed in the middle of the casing and having a slot therein for receiving the twisted portion of the lead 100

holder so as to act as a nut therefor, a second cap rotatable but not longitudinally displaceable in the casing at the end thereof remote from the end having the opening for the lead,
5 said second-mentioned cap having a slot therein for receiving the untwisted portion of the lead holder so as to act as a longitudinal guide for said portion, and a knob on said second-mentioned cap, as and for the
10 purposes set forth.

In testimony whereof I have signed my name to this specification.

HERMANN FELGER.
